UNITED STATES PATENT OFFICE.

WALLACE G. GINDER, OF LOS ANGELES, CALIFORNIA.

DESIGN FOR AN EMBLEM.

52,315.

Specification for Design. Patented Aug. 27, 1918.

Application filed April 23, 1918. Serial No. 230,349. Term of patent 3½ years.

To all whom it may concern:

Be it known that I, WALLACE G. GINDER, a citizen of the United States, residing at Los Angeles, in the county of Los Angeles and State of California, have invented a new, original, and ornamental Design for an Emblem, of which the following is a specification, reference being had to the accompanying drawing, forming part thereof.

The figure is a front elevation of the emblem.

I claim:

The ornamental design for an emblem, as shown.

In witness that I claim the foregoing, I have hereunto subscribed my name this 17th day of April, 1918.

WALLACE G. GINDER.
